IMAGE TRANSMISSION SYSTEM

Reynolds D. Brown, Jr., Philadelphia, Pa., assignor to Philadelphia Storage Battery Company, Philadelphia, Pa., a corporation of Pennsylvania

Application March 21, 1931, Serial No. 524,364

3 Claims. (Cl. 178—6)

This invention relates to image transmission systems and has particular reference to those systems in which the picture or image is transmitted and received by transmitting small elements of the image in a predetermined order to make up the complete image and receiving the elements of the image in the same order to make up the complete received image.

The invention has for its general object the provision of a method of transmitting and for receiving the small elements of the image which will give results heretofore unattainable.

A further object is to provide a method of scanning an object or image which comprises scanning the object in a plurality of non-recurring paths during each complete scanning cycle, whereby the object is resolved into a great number of small scanned areas or elements to bring out detail and eliminate objectionable background lines and flicker.

A still further object is to provide a method of scanning an object or image which comprises scanning the entire image in paths having a general direction and thereafter successively scanning the entire image in paths having a different general direction during a single complete scanning cycle, whereby the image of the object is first generally outlined and then built up gradually to give a higher degree of definition and detail than has heretofore been obtainable.

A further and more specific object of the invention is to provide a device according to this method which will enable the transmission of images of objects or pictures in a manner to more clearly bring out details thereof and to eliminate objectionable background lines and flicker.

A more specific object of the invention is to provide a device utilizing a smaller scanning disc than has heretofore been practical and having the attending advantages thereof. The device also makes use of round holes in the disc, which has added advantages.

Other objects and advantages of my invention will be apparent from the following description in connection with the accompanying drawings, in which:

Fig. 1 shows in elevation a scanning device operating according to the general method of my invention with some parts in section for a clear disclosure thereof;

Fig. 2 illustrates the path traversed by a scanning element of the disc of the device of Fig. 1 and shows the portions of the picture area scanned by the element; and

Fig. 3 illustrates the paths across the picture area traversed by each of the scanning elements during the first revolution of the disc of the device of Fig. 1 about its axis.

Referring to Fig. 1, there is shown in section a base 1 and side wall 2 of a box-like structure which may support and enclose my device. Mounted on base 1 by means of suitable bolts or the like is a supporting member 3, upon which in turn is mounted by any suitable means a motor 4. Motor 4 is provided with a hollow shaft 5 for a purpose to be described later. Mounted on shaft 5 by means of a suitable set screw 6 is an arm 7. As shown, one end of arm 7 has formed thereon a ring member 8 which fits snugly over shaft 5 and has a tapped hole 9 therethrough to receive the threaded set screw 6. Shaft 5 is provided with a depression 10 into which the end of set screw 6 fits. It will be apparent that arm 7 is locked to shaft 5 and will rotate therewith. The opposite end of arm 7 has formed thereon a sleeve 11 through which a shaft 12 passes. The shaft 12 is rotatable within the sleeve and has mounted on one end, by means of a suitable flange 13 and screws 14, a scanning disc 15. The flange 13 may be formed as an integral part of shaft 12. Shaft 12 is also provided with collars 16 mounted thereon in any suitable manner, such as by means of set screws, to prevent the shaft from moving endwise in sleeve 11.

The opposite end of shaft 12 is of smaller diameter and has keyed thereto a pinion 17 which rests against the shoulder of shaft 12. A washer 18, nut 19, and cotter key 20 provide means for locking the pinion on the shaft. The frame of motor 4 is formed so as to have an annular surface 21 with tapped holes 22 therein. A collar member 23 fits snugly over surface 21 and is also provided with holes which coincide with holes 22. Screws 24 pass through the holes of member 23 and threadedly engage the tapped holes 22 to firmly secure collar 23 on the motor frame. Integral with collar 23 is an annular frame 25 having gear teeth 26 formed about the periphery thereof to provide a fixed gear, which meshes with pinion 17. Holes 27 are provided in frame 25 to give access to set screw 6. From the description thus far, it will be apparent that rotation of motor shaft 5 will revolve arm 7, which will carry the axis of the disc 15 in a circular path. The fixed motor frame gear will then cause pinion 17 to rotate, thus rotating the disc 15 about its axis.

The disc 15 comprises the usual scanning disc with spirally arranged apertures or lenses adapted to ordinarily scan horizontal lines of the pic-

ture area. Side wall 2 is provided with an opening 28, about which is fastened in any desired manner, such as by screws 29, a truncated conical member 30 of any suitable opaque material. 5 The smaller opening of member 30 is positioned adjacent the scanning disc 15, so that the spirally arranged scanning elements would, with rotation of the disc about its axis, scan the area of the opening in a series of slightly curved, approximately horizontal paths during each rotation of the disc. It will be understood, of course, that the picture or object to be scanned, in the case of transmission, may be located adjacent the scanning aperture, or an image thereof projected on a 10 screen, and that any lens system may be used if desired. Alternatively, the object or image may be scanned by the beam from a light behind the scanning disc and photocells may be positioned adjacent the object. In the case of reception, the image of the object may be formed on the plate or anode of the lamp.

A support member 31 is mounted on member 3 and is provided with a sleeve 32 at its upper end. 15 A hollow shaft 33 fits snugly within the sleeve and is fastened thereto by means of a winged top set screw 34. Shaft 33 passes through the hollow motor shaft 5 and supports a lamp socket 35, which may be removably mounted on the shaft in any suitable manner. One way, as shown, is to 20 form the socket with a collared end which fits over a small diameter end of shaft 33. A glow lamp 37, having suitably shaped electrodes 38 and 39 to properly illuminate the desired area, is supported by socket 35. It will be understood, of course, that in the case of transmission, a light sensitive cell could be used, or a constant light may be projected. A conductor 40 passes through shaft 33 and is connected to a contact in socket 35, the socket and shaft 33, of course, acting as the 25 other conductor.

In operation, it will be understood that there will be a scanning device at both the transmitting and receiving stations operating in synchronism. At the transmitting station, if the usual system is used, light directed toward the object or picture to be transmitted will pass through the apertures of the disc to the object and will be reflected to vary the current through a light sensitive cell. After being transmitted in any suitable fashion, 30 the variations will be received at the receiving station and will serve to reproduce an image of the object or picture on the plate or anode of the lamp.

The fixed gear and pinion of my device may, of course, be given any desired ratio. I prefer, however, a ratio of six to one so that the pinion rotates six times while passing around the gear once. Since each rotation of the arm 7, irrespective of the fixed gear, carries pinion 17 through an entire revolution with respect to the motor frame, and since the arm and pinion are rotating in the same direction, the speed ratio between the pinion and arm is five to one. In other words, when the arm has rotated once, the pinion has rotated five 45 times on the arm and six times on the fixed gear.

As shown in Fig. 2, while the motor axis makes a single revolution, each scanning element of disc 15 traverses an epitrochoidal path which includes six different but overlapping portions of the area 50 being scanned. In this figure, the disc 15 is shown in an original position and is indicated as having six apertures 41 arranged in spiral. The shaded area represents the area to be scanned. The pinion 17 and gear 26 are represented by 55 broken circles. Now if we consider the path of

any one of the apertures, such as the outermost one, the path will be as indicated by the broken circles and lines. A portion only of the epitrochoidal path is shown for simplicity, but all portions thereof which traverse the area being scanned are as shown. It will be apparent then that during each cycle (revolution of the motor shaft), each aperture will scan six non-recurring, overlapping paths of the area.

During each rotation of the disc about its axis, 10 the apertures will scan the entire area in a series of curved paths, as indicated in Fig. 3. In this figure, the gear 26 and pinion 17 are again represented by broken circles, and the shaded area represents the area to be scanned. The small broken 15 circles and the curved broken lines represent the apertures and their paths across the area during the initial rotation of the disc about its axis. During each of the subsequent rotations of the disc in the cycle, the apertures will scan similar 20 series of non-recurring, overlapping paths but of different directions.

Thus the whole area of the object or picture is scanned at least six times during each revolution or cycle of my device. A speed of two and one-half revolutions per second (150 revolutions per minute) of the motor will give fifteen scanings per second. The disc will then rotate twelve and one-half revolutions per second (750 revolutions per minute). It will be apparent 30 that with my device, a low motor speed is utilized, whereas the devices of the prior art, require a motor speed of nine hundred revolutions per minute, of six times the motor speed of my device, to give the same number of scanings per second. It will be understood, of course, that I have used a six aperture disc for illustration purposes only. A larger disc with a larger number of apertures could be used in practice.

It is to be noted that since the paths of the 40 apertures overlap, as shown in Figs. 2 and 3, the overlapping portions will be scanned by more than one aperture, and each aperture will scan the overlapping portions more than once, during each cycle. In other words, instead of fifteen 45 scanings per second, the area will be scanned more often because the overlapping portions cover practically the entire area. The effect of this is to give fine scanning which gives more detail, reduces flicker, and eliminates background lines.

It will also be noted that my device utilizes and is particularly adapted to a round scanning area. A small scanning disc suffices to scan the entire area. A higher degree of efficiency and perfection using round apertures is attained than has heretofore been possible. The device is compact and free from local mechanical or electrical interference.

Another important advantage of my method 60 of scanning is that electrical disturbances, such as noises and hum, if present, are not reproduced as regular recurring distortions, which are very annoying. With the ordinary method, disturbance impulses produce spaced horizontal disturbance lines or areas on the reproduced image. With the present method, however, the disturbances are reproduced as lines running in different directions giving the effect of a uniform background. Obviously, this is not annoying to the observer, as is the case where regular lines are produced.

The use of a small scanning disc having round holes has numerous advantages and constitutes an important feature of a device using a scan- 75

ning disc for carrying out the scanning method of my invention. A small disc occupies less space than the larger discs which are requisite in prior art devices. Since the diameter of the disc is the largest dimension in such devices, they require as much space as is necessary to accommodate the disc. The disc of my device may be very small, in fact, little larger than the diameter of the motor frame. As a result of the small amount of space required by such a small disc, the latter places no limitation on the space required by the device as a whole. The entire assembly may be housed in a small casing to form a compact device. Such a device requires little space and in addition is more portable than the bulky device made necessary by the use of a large scanning disc. These are important considerations to the average user and would, therefore, bear directly on the commerciality of the device.

Another important feature of a small disc is that it has less inertia. From the standpoint of safety to the user, this is very important. The large scanning disc required in devices of the prior art act much the same as the fly-wheel of an engine due to their high inertia. A large disc, revolving at a speed of say nine hundred revolutions per minute is obviously a menace to the safety of anyone who happens to be near it. If it should break or become loose due to mechanical defects, the damage which it might do is readily apparent. On the other hand, comparatively little damage would be likely to occur if a small disc rotating at a low speed were to break or become loose.

A still further and important feature of a small disc is the fact that it can be made extremely thin. Naturally, the large and cumbersome discs which are required by devices of the prior art have a limiting thickness. That is, the disc must be at least thick enough so that it will not collapse while remaining stationary. Obviously, if a large disc of this kind were made of leaf-like thickness, it would not have sufficient strength to maintain itself rigid while standing still. This may be more readily visualized by considering a disc of large diameter made of paper. It is readily apparent that such a disc would not maintain its rigidity in a stationary state. On the other hand, the disc of my invention may be of such comparatively small diameter that it may be of leaf-like thickness and will still be sufficiently strong to maintain its rigidity while standing still. The advantages of being able to utilize such a thin disc are readily apparent. The most important of these is perhaps the saving in material. Another important advantage is that such a disc enables an observer to view the reproduced image from different positions in front of the disc, whereas with a thick disc the deep walls of the apertures restrict the angle of vision and limit the visible area of the image. The use of a disc having round holes rather than square or other shaped holes also has numerous attending advantages. The most important of these is perhaps the ease with which such a disc may be manufactured accurately. It is a simple matter to punch or bore extremely small holes in a thin sheet of material. However, it is quite difficult to obtain small square or other shaped holes in a similar piece of material. The small round holes may be readily punched or bored in the material whereas the square holes must be obtained by means of suitable dies.

Heretofore, discs using round holes have not

found very successful practical application in devices of the prior art. In my device, however, round holes find successful application and are utilized in a manner to completely scan in fine degree the desired area.

It is to be understood that the specific structure described is for the purpose of illustration only. Manifestly, many changes within the scope of the invention are possible. It is within the scope of my invention to impart to the disc any desired motion in addition to its ordinary revolution. The structure shown could obviously be modified in details. For example, instead of having the motor shaft hollow, an auxiliary hollow shaft could be provided which would be driven by the motor and would have the rotating arm mounted thereon. In this instance, the motor frame could be rotatable so as to enable synchronizing the motors, or the fixed gear which would be mounted on an independent support, could be rotatable.

The method of scanning a given area in non-recurring paths during a complete cycle may be applied by suitable apparatus to the cathode ray scanning device or to the double-drum, perpendicular axis scanning device. A scanning device comprising multiple fixed cells may incorporate my invention if provision is made for actuating cells horizontally in rows and subsequently vertically in rows and then, if desired, in other directions all in a single scanning cycle. It is of utmost importance to note, therefore, that my invention contemplates a method of scanning which may be carried out by numerous devices.

The numerous possibilities and advantages of my method of scanning may be more readily visualized by a study of Figs. 2 and 3 of the drawings. While these figures are intended primarily to illustrate the operation of the device of Fig. 1, they show clearly the method of scanning which my invention in its broad sense contemplates. As illustrated in these figures, the method contemplates the scanning of the object or desired area a plurality of times from different directions during a complete scanning cycle. During the initial portion of the scanning cycle, the area in question is completely scanned in a series of substantially parallel paths from a certain direction. This gives a complete picture and the remainder of the cycle is devoted to building up detail and definition. In the device of Fig. 1, for example, the desired area is completely scanned six times from different directions. Obviously, if the device were stopped after the area had been scanned once, or in other words, at the end of one-sixth cycle, a complete picture would be obtained, although, it would probably be lacking in detail. Each successive scan of the area from different directions builds up or adds to the detail and definition of the picture already obtained. It might be said, therefore, that the method of my device contemplates resolving the picture or desired area into infinitely small portions by scanning from different directions.

The advantage of such a method of scanning which involves resolving the picture area into small portions may be readily appreciated by considering a small portion of the area having, say, a black and white area. If the picture area were scanned once from one direction only, as in the case of the ordinary scanning disc arrangement, the details of the black and white areas of the portion in question might not be properly brought out. However, if the picture area is

scanned a number of times during each cycle from different directions, as in the case of my improved method, the details of the respective areas of the portion in question would necessarily be brought out and made definite by at least one and probably more of the scannings. Considering, for example, a vertical strip or area of the picture, the ordinary method of scanning such area would result in the reproduction of an area having the general contour of tangentially disposed circles, because the scanning apertures merely sweep transversely across adjacent portions of the area. If the scanning method of the present invention is used, however, the area is scanned by having the scanning apertures sweep over the area in different directions during each scanning cycle. Since during one scanning the area will be swept over longitudinally by one or more of the scanning apertures, the image reproduced will be of the same contour as the scanned area, having sharply defined edges. Furthermore, the multiple scanning will greatly increase the definition of the details.

Other advantages resulting from this method of scanning are numerous and may readily be appreciated. For example, in the transmission of still pictures, with the ordinary device of the prior art, the operator receiving the picture must receive a complete cycle before he can determine the details of the picture. If he is uncertain as to whether or not he desires to receive the particular picture, he must, nevertheless, receive an entire cycle to find out whether or not he desires it. In the transmission of still pictures utilizing the method of my invention, however, the initial fraction of a cycle will give a complete picture. If this picture does not have sufficient detail so that the operator can intelligently understand it, he can receive another fraction of the cycle which builds up the details of the picture. Thus, each succeeding fraction of the cycle, during which the picture area is completely scanned, builds up or adds to the detail of the picture transmitted during the first fraction of the cycle.

In the case of a device using a scanning disc to carry out my improved method, it is conceivable that the disc might be imperfect or that a hole might become clogged by foreign material, the disc might be imperfect in that one of the apertures or scanning elements might, for example, be slightly out of place. If either of these contingencies occurred in devices of the prior art, wherein the picture area is scanned only once from a single direction during each cycle, it is readily perceivable that a distorted or imperfect picture would result. If a hole in the disc were slightly out of place, there would be an area of the picture which would not be transmitted at all and another area in which the details would overlap. If one of the holes become clogged, there would be an area of the picture which would not be transmitted.

Consider now what would happen if either of these contingencies occurred in a device operating according to my scanning method. During the initial fraction of a cycle, when the picture area is completely scanned, there would be an area which would not be transmitted, but the succeeding scannings of the picture area from different directions during the remainder of the cycle would cause the omitted area of the picture to be transmitted. Of course, in any such case, the picture received would not be as perfect as if such contingency had not occurred. How-

ever, in all probability, the defects in the picture would not be noticeable. In other words, the method of scanning, which my invention contemplates, might be said to spread the error out over the entire picture, making it less apparent, much the same as the spreading of any material in a layer, rather than having it concentrated in a pile, serves to make it thinner and less apparent.

In the case of a device for using a cathode ray to scan the desired picture or object, it is conceivable that the mechanism which controls the ray and causes it to move in a spiral might get out of adjustment. Usually, a pair of condensers having their plates on opposite sides of the ray are used to control the movement thereof, as is well known in the art. Voltages are applied to the condenser plates, setting up electrostatic fields which influence the ray in the desired manner. It is easily conceivable that the voltages applied to the condenser plates might not always be exactly equal. For example, if they were unequal, instead of the cathode ray describing a true spiral path, it would describe a distorted spiral path which would take an elliptical form rather than a circular form. The result of this is clearly obvious. The picture would be distorted to the same degree that the controlling voltages are unequal. One receiving such a picture would have difficulty in intelligently discerning the details thereof, if the picture were not entirely unintelligible.

If the method of my invention is applied to a cathode ray device, the ray, in addition to generating successive spirals would also be moved to obtain successive scanning of the entire picture area in non-recurring paths during each cycle. If the voltages applied to the condenser plates of the device were unequal, as assumed above, any one scanning of the picture area during a fraction of the scanning cycle, would give a distorted picture in the same manner as the ordinary cathode ray device. However, the successive scannings of the complete picture area during the other fractions of the scanning cycle would tend to balance the distortion and spread it out over the entire picture. A fair picture would at least be obtained and would be intelligible to the person receiving it.

A still further advantage of the present method resides in the fact that no limitations are placed upon the dimensions or shape of the scanning area. In devices of the prior art, radial and circumferential limits of the area cause distortion. The upper and lower boundary lines of the scanning area are circumferential with respect to the disc axis, and the side margin lines are radial with respect to such axis. For this reason, the radial distance between the innermost and outermost apertures of the disc must be small compared to the radius in order to give a practical shape to the scanning area. Obviously, such limitation is not present in my device and the disc apertures may be located as close as is practical to the disc axis.

Another important advantage of my method is that it enables the attainment of improved definition notwithstanding the limitations imposed on such systems by broadcast authorities. The regulation of such systems by the authorities may impose definite limits on the number of lines or areas scanned per second, or on the number of disc apertures for a particular speed. Obviously, better definition and detail may be obtained within the prescribed limit or with a certain number of pulses per second with my method.

than could be obtained with prior art methods under the same circumstances.

The above pointed out advantages of my method of scanning are only a few which serve to illustrate the many advantages which are inherent in such a method. Many others will undoubtedly occur to persons skilled in the art. Since, as heretofore pointed out, my invention comprises broadly a method of scanning rather than any particular scanning device or system, it is to be understood that the device illustrated in Fig. 1 is for the purpose of illustration and disclosure only. My invention contemplates and is intended to cover any device which may be utilized to carry out the desired method of scanning. I desire it to be understood, therefore, that my invention is not to be limited by this disclosure but only by the prior art as reflected in the scope of the appended claims.

20 I claim:

1. In an image transmission system, a scanning disc having a plurality of spirally ar-

ranged scanning elements, means for moving the axis of said disc in a circular orbit which lies in a plane perpendicular to the axis of the disc, and means for simultaneously rotating said disc about its axis.

2. In an image transmission system, a scanning disc having spirally arranged scanning elements mounted on a shaft having a pinion, a motor having a rotatable shaft, means associated with said motor shaft for moving the axis of said first shaft in a circular orbit, and stationary means associated with said pinion for rotating said first shaft.

3. In an image transmission system, a scanning disc having spirally arranged scanning elements mounted on a shaft having a pinion, a motor having a rotatable shaft, an arm connecting said shafts whereby the axis of said first shaft is moved in an orbit, and a fixed gear meshing with said pinion whereby said first shaft is rotated.

REYNOLDS D. BROWN, JR.
